CLAIM

The ornamental design for a garment as shown and described.

DESCRIPTION

FIG. 1 is a front left perspective view of a garment showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The short evenly spaced broken lines depict stitching which forms part of the claimed design. The long, evenly spaced broken lines depict portions of the garment that form no part of the claimed design. The dash-dot-dash broken lines are boundary lines that form no part of the claimed design.
